IGNITION DISTRIBUTOR

Harold J. Cromwell, Anderson, Ind., assignor to General Motors Corporation, Detroit, Mich., a corporation of Delaware

Filed July 28, 1961, Ser. No. 127,598

12 Claims. (Cl. 200—30)

This invention relates to an ignition distributor for controlling the spark timing in an ignition system of an internal combustion engine.

In ignition distributors it is necessary to maintain a given effective distance between the adjacent terminals in the distributor cap so as to prevent electrical leakage between the terminals of the cap or between the contact on a distributor rotor to the incorrect terminal in the cap. The distance required between corresponding terminals depends on the peak voltage handled.

In order to prevent the high voltage handled by the distributor from jumping to the incorrect terminal, it is desirable that the rotor be correctly aligned with the correct terminal in the cap when the voltage is to be impressed on a particular spark plug. This condition is maintained on certain model of distributors by the centrifugal advance mechanism because the cam and rotor of the distributor rotate as a unit. However, this condition is not maintained during vacuum advance on most distributors, because the breaker contacts and consequently the spark timing are shifted relative to the cap. If this latter condition could be corrected, the size of the present distributor could be reduced and if desired could be used to handle higher voltage than is now possible.

It accordingly is one of the objects of this invention to provide a distributor apparatus wherein the vacuum advance mechanism will not alter the correct functioning of spark distribution to the correct electrode or terminal in the distributor cap.

A more specific object of this invention is to provide the distributor cap with an insert that is rotatable with respect to the cap and which has contacts that engage the terminals of the distributor cap, the insert being mechanically connected to rotate with the breaker plate of the distributor whereby the insert is shifted during vacuum advance.

Another object of this invention is to provide a distributor cap with an insert member that is formed of insulating material and which carries a plurality of generally arcuately extending contacts that slidably engage the terminals of the distributor cap, the insert member being connected with the breaker plate of the distributor by an upstanding arm which is secured to the breaker plate and to the insert member.

Further objects and advantages of the present invention will be apparent from the following description, reference being had to the accompanying drawings wherein a preferred embodiment of the present invention is clearly shown.

In the drawings:

FIGURE 1 is a sectional view of a distributor made in accordance with this invention.

FIGURE 2 is a sectional view taken along line 2—2 of FIGURE 1.

FIGURE 3 is a plan view of an insert member which forms a part of the distributor made in accordance with this invention.

FIGURE 4 is a sectional view taken along line 4—4 of FIGURE 3.

FIGURE 5 is a plan view showing a side of the insert member opposite to that illustrated in FIGURE 3.

Referring now to the drawings, and more particularly to FIGURE 1, the reference numeral 10 designates the

2

base of a distributor. The base 10 has a central bore which receives a bearing 12 in which is journaled the shaft 14. The base 10 may extend downwardly for a considerable distance as is well known to those skilled in the art and another bearing or bushing may be supported in the lower end of the base 10 to journal the shaft 14 in its rotation. The shaft 14 is, of course, driven by the internal combustion engine on which the distributor is used.

Fitted on the shaft 14 is a conventional cam member 16 which is driven by and slightly rotatable with respect to the shaft 14 and which is connected with a plate member 18 which forms a part of a conventional centrifugal advance mechanism generally designated by reference numeral 20. This centrifugal advance mechanism may be of the type illustrated in the Hartzell et al. Patent 2,872,537. This centrifugal advance mechanism, as is well known to those skilled in the art, will adjust the cam member 16 relative to the shaft 14 in accordance with the speed of rotation of the shaft 14.

The part 18 that forms a portion of the centrifugal advance mechanism 20 supports a rotor which is generally designated by reference numeral 22. This rotor is conventional and is formed of part 24 that carries overlapping electrodes 26 and 28. The part 24 as is well known to those skilled in the art, is formed of insulating material and the electrode 26 is a spring metal electrode. The rotor 22 is secured to the part 18 by fasteners 27 and this part of the distributor is all of conventional construction.

The top end of bushing 12 journals a breaker plate which is designated by reference numeral 30. The breaker plate 30 is rotated with respect to the bushing 12 by a vacuum unit 32 having a rod 34 formed with an upturned portion 36 that passes through an opening in the breaker plate 30. The vacuum unit 32 contains the usual diaphragm, not shown, for shifting the rod 34 and the usual spring for urging the diaphragm in one direction. This vacuum unit is conventional and may be of the type illustrated in the above noted Hartzell et al. Patent 2,872,537.

The breaker plate 30 carries the usual contact set designated in its entirety by reference numeral 38. This contact set is secured to the breaker plate 30 to rotate therewith and includes a breaker arm 40 pivotally supported on a post 42. The breaker arm 40 carries a breaker contact 44 which cooperates with a fixed breaker contact 46. The breaker arm 40 carries a rubbing block 48 which cooperates with the cam 16 in a manner well known to those skilled in the art. It is seen that as the vacuum unit adjusts the breaker plate 30 around the axis of the shaft 14, the spark timing of the distributor is adjusted since the contact set 38 which moves with the breaker plate 30 will be adjusted relative to the cam 16.

The distributor cap for the distributor of this invention is designated in its entirety by the reference numeral 50. This distributor cap is formed of a moldable plastic material and has a plurality of circumferentially spaced electrodes or terminals 52 which are to be connected by suitable leads with the spark plugs on an internal combustion engine. For an eight cylinder engine there will be eight equally spaced electrodes 52 in the distributor cap. The lower ends 52a of the terminals 52 are machined or otherwise formed flat for the purpose to be more fully described hereinafter. The distributor cap has a center electrode or terminal 54 including a ball contact 56 which engages the portion 58 of spring metal contact 26. As the rotor 22 rotates the ball contact 56 is in constant engagement with the portion 58 of the spring metal contact 26.

The center electrode 54 of the distributor cap 50 pivotally supports an insert member generally designated by

reference numeral 60. This insert member is better illustrated in FIGURES 3 through 5 and has a body portion 62 formed of a moldable plastic material. The body portion 62 carries eight terminals or electrodes 64, that have the same spacing as the terminals or electrodes 52 of the distributor cap 50. The top side of the terminals 64 are machined or otherwise formed flat and are generally arcuately shaped as is apparent from an inspection of FIGURE 3. The terminals 64 project through the body portion 62 of the insert member 60 and the lower ends of these contacts are cut away to form generally arcuately extending walls 64b. The body portion 62 of the insert member 60 is shaped to provide a slot 66 and to provide annular slots 68 and 70. The body portion is also formed with an upstanding annular skirt section 72 as is clearly apparent from the drawings.

The insert member 60 has a central opening 74 which receives the center electrode 54 of the distributor cap 50. The center electrode 54 carries a retainer 76 and a spring 78 is interposed between the retainer and the insert member 60. A downwardly projecting portion 80 of the distributor cap fits within the annular slot 70 of the insert 60. The flat surfaces 64a of the contact 64 engage the flat surfaces 52a on the terminals or electrodes 52 located in the distributor cap. The surfaces 64a are of sufficient length so that contact is maintained between the terminals 52 and 64 even though the insert 60 is rotated to some extent.

It can be seen that with the arrangement that has just been described the insert member 60 is rotatably supported by the center electrode 54 and that spark impulses are transferred between the center electrode 54 and the electrodes 52 of the distributor cap by the rotor contacts 26 and 28. In this connection, it is seen that the end of rotor contact 28 passes in close proximity to the arcuate walls 64b of the terminals 64.

The insert member 60 is mechanically connected with the breaker plate 30 so that they rotate together. To this end, a bracket member 82 is secured to the breaker plate 30 by means of a screw fastener 84. The bracket member 84 carries an arm 86 which is riveted or otherwise secured to the bracket member 82. The top end 88 of the arm member 86 fits within the slot 66 formed in the insert member 60 and it therefore is seen that as the breaker plate 30 rotates the insert member 60 is rotated therewith. It will be apparent that other means might be used to connect the breaker plate 30 and the insert member 60 without departing from the spirit and scope of this invention.

It can be seen that with the use of the insert member 60 the correct electrode or terminal of the distributor cap 50 is maintained connected with the center electrode 54 by the rotor contacts 26 and 28 even though the spark is advanced by a shiftable movement of the breaker plate 30. This is true since the insert member 60 must rotate at all times with the breaker plate 30 and contact is maintained between the terminals 52 of the distributor cap and the terminals 64 of the insert due to the elongated surfaces 64a of the terminals 64. As has been pointed out above, the use of the insert member permits a reduction in size of the distributor and also permits the use of higher voltages for the ignition system.

While the embodiment of the invention as herein disclosed constitutes a preferred form, it is to be understood that other forms might be adopted.

What is claimed is as follows:

1. An ignition distributor comprising, a base member, a shaft journaled for rotation in said base member, a breaker plate shiftable relative to said base member carrying breaker contact apparatus, a cam member driven by said shaft cooperating with said breaker contact apparatus, a rotor member driven by said shaft having contact means, a distributor cap carried by said base member including a projecting current carrying center electrode and a plurality of outer circumferentially spaced

electrodes, an insert member formed of electrical insulating material having an opening receiving said center electrode whereby said insert member is supported for rotation on said center electrode of said distributor cap, 5 said insert member having a plurality of circumferentially spaced electrodes that are in engagement with the outer circumferentially spaced electrodes of said distributor cap, the contact means of said rotor being electrically connected with said center electrode and swinging in close proximity to portions of the electrodes of said insert member, and means mechanically connecting said breaker plate and said insert member whereby they move together.

2. An ignition distributor comprising, a base member, a shaft rotatable with respect to said base member, a breaker plate shiftable relative to said base member carrying breaker contact apparatus, a cam member rotatably driven by said shaft cooperating with said breaker contact apparatus, a rotor member including contact means driven by said shaft, a distributor cap supported by said base member including a center electrode and a plurality of outer circumferentially spaced electrodes, said contact means on said rotor member being electrically connected with the center electrode of said distributor cap when said distributor cap is in place on said base member, an insert member rotatably supported by means fixed with respect to said distributor cap including a body member formed of electrical insulating material which supports a plurality of circumferentially spaced electrodes that are in sliding engagement with the outer circumferentially spaced electrodes of said distributor cap, and separable connecting means connecting said breaker plate and said insert member, and an opening in said insert member, said center electrode projecting through said opening to make said electrical connection with said contact means of said rotor member.

3. An ignition distributor comprising, a base member, a shaft rotatable with respect to said base member, a breaker plate carrying breaker contact apparatus shiftable relative to said base member, a cam member rotatably driven by said shaft cooperating with said breaker contact apparatus, a rotor member driven by said shaft including contact means, a distributor cap supported by said base member formed of a plastic insulating material and carrying a center electrode and a plurality of outer circumferentially spaced electrodes, the contact means of said rotor being electrically connected with the center electrode of said distributor cap, an insert member formed of electric insulating material rotatably supported by means fixed with respect to said distributor cap and carrying a plurality of circumferentially spaced electrodes that are in engagement with the electrodes of said distributor cap, said insert member having an opening receiving said center electrode of said distributor cap, the electrodes of said insert member electrically connecting the contact means of said rotor with the outer electrodes of said distributor cap, slot means formed in said insert member, and arm means connected with said breaker plate fitting within the slot means of said insert member whereby said insert member and breaker plate are separably connected.

4. An ignition distributor comprising, a base member, a shaft rotatable with respect to said base member, a breaker plate shiftable relative to said shaft carrying breaker contact apparatus, a cam member driven by said shaft cooperating with said breaker contact apparatus, a rotor member driven by said shaft positioned above said cam member, said rotor member carrying contact means, a distributor cap supported by said base member including a current carrying center electrode and a plurality of outer circumferentially spaced electrodes, an insert member formed of electric insulating material having an opening receiving said center electrode whereby said insert member is rotatably supported directly on the center electrode of said distributor cap and positioned between said 75 rotor and the top wall of said distributor cap, said in-

sert member carrying a plurality of circumferentially spaced electrodes that are in engagement with the outer circumferentially spaced electrodes of said distributor cap and having projecting portions located in close proximity to the contact means of said rotor member, and arm means connected with said breaker plate and extending upwardly into engagement with said insert member whereby said breaker plate and insert member move as a unit.

5. A distributor cap for an ignition distributor comprising, a body portion formed of electric insulating material, said body portion supporting a current carrying center electrode and a plurality of circumferentially spaced outer electrodes, and an insert member formed of electric insulating material rotatably supported by means fixed with respect to said distributor cap, said insert member having a plurality of circumferentially spaced electrodes that engage the outer electrodes carried by the body portion of said distributor cap and having an opening receiving said center electrode.

6. A distributor cap for an ignition distributor comprising, a generally cup-shaped body portion formed of electric insulating material, a current carrying center electrode and a plurality of outer circumferentially spaced electrodes carried by the top wall of said body portion, and an insert member formed of electric insulating material rotatably supported by means fixed with respect to said distributor cap, said insert member carrying a plurality of circumferentially spaced electrodes and having an opening receiving said center electrode, each of said electrodes having a generally arcuately extending surface in engagement with a surface of the outer electrodes supported by the body portion of said distributor cap and having generally arcuately extending lower surfaces adapted to cooperate with the contact means of a rotor.

7. A distributor cap for an ignition distributor comprising, a body portion formed of electric insulating material, said body portion supporting a center current carrying electrode and a plurality of outer circumferentially spaced electrodes, and an insert member formed of electric insulating material, having an opening receiving said center electrode whereby said insert member is journaled for rotation directly on said center electrode, said insert member having a plurality of circumferentially spaced electrodes that are in engagement with respective outer electrodes carried by said body portion.

8. A distributor cap for an ignition distributor comprising, a generally cup-shaped body portion formed of electric insulating material, said body portion having a top wall supporting a current carrying center electrode and a plurality of outer circumferentially spaced electrodes, and an insert member formed of electric insulating material having an opening receiving said center elec-

trode whereby said insert member is journaled for rotation on said center electrode, said insert member having a plurality of circumferentially spaced electrodes that pass through the insert member, the top surfaces of the electrodes in said insert member being elongated and generally arcuately extending and contacting a surface of the outer electrodes in said body portion, the electrodes in said insert member having downwardly extending portions formed with generally arcuately extending surfaces that are adapted to cooperate with contact means carried by a rotor of a distributor.

9. A distributor cap for an ignition distributor comprising, a body portion formed of electric insulating material, said body portion supporting a center current carrying electrode and a plurality of outer circumferentially spaced electrodes, an insert member formed of electric insulating material having an opening receiving said center electrode whereby said insert member is journaled for rotation directly on said center electrode, said insert member having a plurality of circumferentially spaced electrodes that are in sliding engagement with respective outer electrodes carried by said body portion, and inter fitting means disposed respectively on said cap and insert member for preventing cocking of said insert member.

10. The distributor cap according to claim 9 wherein the inter fitting means comprises an annular projection on the cap and an annular recess on the insert member which receives the annular projection on the cap.

30 11. A distributor cap for an ignition distributor comprising, a body portion formed of electric insulating material, said body portion supporting a center current carrying electrode and a plurality of outer circumferentially spaced electrodes, an insert member formed of electric insulating material having an opening receiving said center electrode whereby said insert member is journaled for rotation directly on said center electrode, said insert member having a plurality of circumferentially spaced electrodes that are in sliding engagement with respective outer electrodes carried by said body portion, and retaining means for retaining said insert member on said center electrode.

40 12. The distributor cap according to claim 11 wherein the retaining means includes a spring.
